UNITED STATES PATENT OFFICE.

JOSEPH WOJTASIEWICZ, OF CHADWICKS, NEW YORK.

SNOWPLOW.

1,328,026.

Specification of Letters Patent. Patented Jan. 13, 1920.

Application filed May 16, 1919. Serial No. 297,548.

To all whom it may concern:

Be it known that I, JOSEPH WOJTASIEWICZ, a citizen of Poland, residing at Chadwicks, in the county of Oneida and State of New York, have invented certain new and useful Improvements in Snowplows, of which the following is a specification.

The primary object of the invention is the provision of means for quickly removing snow and ice from a roadway such as a street car track, the structure being exceedingly strong for cutting its way through accumulations of snow and being readily controlled by a single operator.

A further object of the invention is the provision of a snow plow in the nature of a car adapted for traveling upon a track and having power means for cutting through ice and snow during forward travel as well as cleaning means for the cutters whereby the invention is more efficient in its operation.

With these general objects in view the invention consists of the novel combination and arrangement of parts hereinafter more fully described in connection with the accompanying drawings and in which like reference characters designate corresponding parts throughout the several views.

In the drawings,

Figure 1 is a side elevation of the invention,

Fig. 2 is a longitudinal vertical sectional view thereof,

Fig. 3 is a horizontal sectional view of the same,

Fig. 4 is a front elevation of the invention with parts broken away,

Fig. 5 is an enlarged detail sectional view of a portion of the blowing means, and

Fig. 6 is a substantially horizontal sectional view thereof taken also through the adjacent cutting member.

My invention contemplates the provision of a car 10 similar in form to the usual street car with wheels 11 adapted for travel upon a track 12, any desired form of motive power being provided, such as an electric locomotive, not shown, adapted for pushing the car 10 forwardly upon the track 12.

The forward end 13 of the car 10 is V-shaped in horizontal cross section having side members 14 terminating downwardly in a pointed plow portion 15 adjacent the track 12.

A plurality of shafts 16 herein shown as two in number, are journaled upon each side of the car front 13 by means of brackets 17 and 18 secured to the side portions 14 and 15 respectively.

The shafts 16 are positioned forwardly inclined with sets of cutters or blades 19 secured around the shafts in spaced relations and alternately arranged upon the adjacent shaft 16 for rotary movement in intermediate planes as best indicated in Figs. 1 and 4 of the drawings.

Air pipes 20 are secured inwardly of the sides 14-15 rearwardly of the shaft 16 and are provided with forwardly projecting nozzles 21 for blowing air upon the cutters 19 of each shaft 16.

A power gear 22 is carried by a shaft 23 journaled transversely of the car 10, the said gear projecting through an opening 24 of the bottom 25 of the car in constant mesh with a pinion 26 carried by the revolving axle 27 of one of the track wheels 11. The gear 22 meshes with a pinion 28 upon a shaft 29 transversely within the car 10, while a clutch member 30 is also carried by the shaft 29. A clutch member 31 adapted to coöperate with the member 30 is slidably mounted upon the shaft 29 with a sprocket wheel 32 secured to the clutch member 31 for revolving therewith, the said sprocket wheel being connected by means of a chain 33 with a similar sprocket 34 carried by a shaft 35 journaled in brackets 36 adjacent the forward end of the car 10.

A hub 37 slidable upon the shaft 29 with the wheel 32 and the clutch member 31 has an operating rocker arm 38 connected by a rod 39 with an actuating lever 40 adjacent the rear end of the car. It will be apparent that upon shifting the lever 40 forwardly, the rod 39 and arm 38 will force the hub 37, wheel 32 and clutch member 31 toward the clutch member 30 thereby engaging the clutch members 30 and 31 for turning the shaft 35 by means of the tractor wheel 11. The lever 40 has the usual retaining means 41 for engaging a toothed segment 42, the reverse or rearward movement of the lever 40 being adapted to bring the clutch member 31 out of engagement with the positively driven clutch member 30 to the inoperative position shown in Figs. 2 and 3 of the drawings.

An operating shaft is journaled through the sides 14 for each of the shafts 16, beveled pinions 44 being provided upon the inner ends of the shafts 43 in constant mesh 5 with similar pinions 45 secured upon the shaft 35. Beveled pinions 46 upon the outer ends of the shafts 43 are in constant mesh with similar pinions 47 upon the upper ends of the shafts 16 and whereby the shafts 16 10 and cutters 19 are forcibly revolved by turning the shaft 35 in the manner heretofore noted. The pinions 45 are oppositely set at the opposite sides of the sprocket wheel 34 providing opposite engagement with the 15 shafts 43 through the opposite sides 14, so that the opposite pairs of cutting members simultaneously revolve in opposite directions when plowing through snow and ice.

A pump 48 within the car 10 has a piston 20 member 49 operatively connected by a rod 50 with a crank portion 51 of a transverse shaft 52 journaled in the car 10. A clutch member 53 fixed to the shaft 52 is adapted for engagement by a clutch member 54 25 slidable upon the shaft 52 with a sprocket wheel 55 slidable therewith and connected by a chain 56 with a sprocket 57 upon the slidable hub 37.

A hub 58 attached to the sprocket 55 and 30 clutch member 54 is slidable upon the shaft 52 while a rocker arm 59 is connected by a rod 60 with a lever 61 for readily shifting the arm 59, throwing the clutch member 54 into and out of engagement with the clutch 35 member 53 at will. The outlet pipe 62 of the pump 48 is controlled by a valve 63 within the car 10 and has branch connections 64 with air pipes 65 extending forwardly of the car and each having branches 66 connected to 40 the outlet pipes 20 whereby air may be forced through the nozzles 21 at will. The manner of operatively connecting the cutter shafts 16 with the power shaft 29 through the clutch members 30—31 by means of the lever 45 40 having been described, it will be seen that when the clutch 30—31 is closed, that the chain 56 will turn the sprocket 55 and clutch member 54 so that upon forwardly moving the lever 61 for engaging the clutch member 54 with the clutch member 53, the shaft 52 50 will be revolved for operating the hub 58. The cutting operation may be effected either with or without the employment of the blowing nozzles 21 but the pump 48 for the blowing 55 nozzles 21 is incapable of operation when the cutter shafts 16 are idle. The opposite pairs of shafts 16 are preferably revolved outwardly for cutting and throwing the snow in opposite directions while the blowing nozzles 21 60 free the cutters 19 from snow rendering the continuous operation of the cutters possible during the forward movement of the car 10. A suitable form of scrapers 67 are preferably positioned beneath the car 10 projecting

from the opposite sides thereof and assisting to clean the track 12 of snow and ice operated upon by the cutters 19. An inclined bottom 68 is preferably provided for the plow portion 15 of the car front so that the entire car is substantially inclosed for 70 operation during cold weather.

Having thus described my invention what I claim and desire to secure by Letters Patent is:—

1. A snow plow comprising a car with a 75 pointed forward end, pairs of inclined shafts journaled upon the opposite sides of said forward end, snow cutters upon said shafts, a transverse power shaft within the forward portion of the car, operative connections between said power shaft and cutter shafts whereby the cutter shafts upon the opposite sides of the car are adapted for simultaneous operation in opposite directions, and air blasting nozzles alined with 80 the snow cutters for removing snow therefrom during operation.

2. In combination with a car having track wheels, a forward end of the car arranged in V-shaped formation, a shaft transversely 90 journaled within the forward portion of the car, a pair of cutting members journaled exteriorly of the car upon the opposite sides of the forward end thereof, connecting members geared between said cutting means and transverse shaft whereby the cutting means at one side of the car is adapted for rotation simultaneously and in a direction opposite to the cutting members at the opposite sides of the car, and air blasting nozzles alined with the 95 cutting members for cleaning the same of snow during operation.

3. In combination with a car having track wheels, a power shaft within the car operatively geared to said wheels, cutting means 105 positioned upright outwardly of the forward end of the car on opposite sides thereof, clutching means adapted for detachable engagement with said power shaft, operatively connected to said cutting means, an air pump 110 within the car, a clutch member for the air pump adapted for rotation with said clutching member of the cutting means whereby the pump is adapted for actuation by the track wheels only during the operation of said 115 cutting means and air blast means connected to said pump positioned upon the forward end of the car directed toward the said cutting means.

4. In combination with a car having a 120 tapered forward end, inclined shafts journaled upon the opposite sides of said forward end, cutters secured to said inclined shafts in intermediate planes, pinions upon the upper ends of said shafts, a power shaft 125 within the car, connecting means journaled through the forward end of the car having geared connections with said pinions, oppo-

sitely arranged pinions, connections between said connectors and power shaft whereby the inclined shafts are adapted for rotation in different directions at opposite sides of
5 the car, operating means for said power shaft, air pipes within the forward end of the car, air blast nozzles upon said pipes

forwardly projecting in the direction of said cutters, air supplying means for said pipes adapted for operation only during the rotation of said power shaft. 10

In testimony whereof I affix my signature.

JOSEPH WOJTASIEWICZ.
